APPARATUS FOR CLEANING STRIP MATERIAL

Charles R. Russell, Homewood, and Edward A. Schulz, Clarendon Hills, Ill., assignors to Western Electric Company, Incorporated, New York, N.Y., a corporation of New York

Filed June 2, 1958, Ser. No. 739,109

3 Claims. (Cl. 15—102)

This invention relates to an apparatus for cleaning strip material and more particularly a cleaning apparatus having detachably mounted abrasive pads for engaging and cleaning both sides of a strip material passing through the apparatus.

In cleaning operations for moving strip material where an abrasive pad is used for cleaning that must be changed quite often, it is necessary to provide a quick detachable pad holding mechanism. It is a requisite that the holding mechanism restrain the pad against longitudinal movement with the moving strip while not engaging the strip.

It is a primary object of this invention to provide an abrasive holding apparatus permitting rapid and uncomplicated changing of the abrasive.

Another object of this invention is to provide an apparatus for cleaning moving strip material wherein the holder for retaining a compressible abrasive pad does not engage the moving strip.

Still another object of this invention is to provide a strip cleaning apparatus which can be pivoted out of engagement with the strip material to facilitate changing of the cleaning abrasive.

With these and other objects in view the present invention contemplates an apparatus for cleaning strip material wherein grooved blocks are pivotally connected with the grooves of one block facing the grooves of the other. One of the blocks is resiliently mounted and both blocks are provided with grills pivotally mounted thereon below the surface of the block and congruent with and movable into the grooves of the block to which the grill is mounted. Each of the grills has a latching means to hold the grill in the grooves and thereby force a portion of a compressible abrasive pad into the grooved surfaces of the blocks to secure the pad against longitudinal movement with a strip moving past the pad. In this latched position the grills are out of the plane of the engaging surface of the abrasive pads. The blocks are held in position on opposite sides of the strip material with the abrasive pad in frictional contact therewith by a quickly releasable latch means that tends to force the blocks together.

Other objects and advantages of the invention will become apparent by reference to the following detailed description and the accompanying drawings wherein:

Fig. 1 is a side elevational view of a cleaning apparatus, with pads of steel wool held in abrasive contact with a moving strip, constructed in accordance with the principles of the invention.

Fig. 2 is a top view of the cleaning apparatus showing the relative placement of latch fasteners and steel wool pad retaining grills.

Fig. 3 is an end view of the cleaning apparatus in open position with the grills pivoted out of grooves formed in supporting blocks.

Fig. 4 is a cross sectional view along lines 4—4 showing the cleaning apparatus locked in operative position with the rods of the grill and a portion of the steel wool pads held in the grooves of the block.

2

Fig. 5 is a cross sectional view along lines 5—5 showing the cleaning apparatus latched into cleaning position and showing a resilient mounting for the upper block.

Referring to Figs. 1-3 there is illustrated a cleaning apparatus having a stand 20 and a frame 21 pivotally mounted to the stand 20 by a pin 22. The frame 21 is held in a horizontal position by a pair of brackets 25 pivotally connected to the frame 21 by a pin 26 and adjustably connected to the stand 20 by a slot 27 and a bolt 28. A wooden block 35 is supported on the frame 21. A plurality of levers 36 each having a bolt 37 adjustably secured thereto (Fig. 3), are pivotally mounted to the frame 21 by a plurality of pins 38. The bolts 37 are adjustably mounted in levers 36 so that the levers 36 can be moved to provide predetermined separations between the levers 36 and the block 35 when the levers 36 are pivoted counterclockwise about the pins 38 (Fig. 3) to a horizontal position over the block 35.

A second or cover block 45 (Fig. 5) is resiliently mounted to the levers 36 by screws 47 that pass through openings 48 in the levers 36 to threadably engage the block at the bottom of recesses 46. A spring 50 is mounted on each screw 47 between each lever 36 and the bottom of each recess 46 to bias the block 45 away from the levers 36 (Fig. 5).

The block 35 is provided with a group of longitudinal grooves 55 and 56 (Fig. 5) that communicate with a series of lateral dovetail grooves 57. A grill 60 having longitudinal elements 62 and 63 and lateral elements 64 is congruent with and positioned to fit loosely within the longitudinal grooves 55, 56 and lateral grooves 57. The longitudinal element 62 of the grill 60 is pivotally mounted by a row of four hinge rods 65 extending upwardly from the base 21 so that the rod 62 is confined in the slot 55 of the block 35.

The grill 60 being thus pivotally mounted by the hinge rods 65 can be pivoted towards the grooved surfaces in the block 35 to allow the longitudinal rod 63 to move into the longitudinal slot 56 in the block 35 and to force the lateral grill elements 64 into the lateral block grooves 57. Four latch bar members 70 are pivotally secured to the rod 63 of the grill 60 and are movable into open slots 72 and 73 (Fig. 5) formed in the block 35 and the frame 21 respectively. A wing nut 75 is threadably mounted on the latch bar 70 to act against frame 21 (Figs. 1 and 5) to draw the grill 60 into the lateral grooves 57 and the longitudinal grooves 66 of the block 35. A steel wool pad 76 or other compressible abrasive material having a low cohesive strength is placed over the grooved surface of the block 35 before the grill 60 is pivoted into the grooves 56 and 57 will be held to the grooved surface of the block 35 by forcing portions of the steel wool into the grooves.

The block 45 has lateral dovetail grooves 79 (Figs. 1, 2 and 4). A grill 80 having longitudinal rods 82 and 83 and lateral rod elements 84, is adapted to fit loosely within the grooves 79 of the block 45. The longitudinal rod 82 of grill 80 is pivotally mounted to four hinge rods 85 which are threadably secured to the levers 36 so that the rods 82 of the grill 80 will be in the general plane of the grooves 79 of the block 45. The grill 80 is thereby pivotally mounted to the hinge rods 85 so as to be able to pivot the lateral rods 83 into the grooves 79 and out of the plane of the working surface of the steel wool.

Four latch bars 87 are pivotally connected on the longitudinal bar 83 of the grill 80 (Figs. 1, 4 and 5) and move into slots 88 formed in a series of levers 89. Wing nuts 90 are threadably mounted on the latch bars 87 to act against the levers 89 to draw the grill 80 into the lateral grooves 79 of the block 45. A steel wool pad 91 or other compressible abrasive material placed over the grooved surface of the block 45 before the grill 80

is moved into the grooves 79, is held against the groove surface of the block 45 by forcing a portion of the steel wool into the grooves.

After the wing nuts 90 and 75 are tightened to hold the block 45 rigidly against the frame 21 and the block 35 resiliently against levers 36 (Figs. 4 and 5), the levers 36 are pivoted over the base 21. Two latch rods 91 are pivotally connected to frame 21 by pins 92 and can be moved into slots 93 formed in the frames 36. Wing nuts 95 which are threadably mounted on the latch bars 91 can be tightened against the levers 36 (Figs. 1, 4 and 5) to draw the upper block 45 toward the lower block 35 to force the steel wool pad 91 against one side of a moving strip 100 to be cleaned and simultaneously force the steel wool 76 secured to the lower block 35 against the underside of the strip 100. The abrasive to be used could also be in the form of an abrasive sheet or pre-shaped block with grooves to receive the holding grill rods.

Operation

Assume that the apparatus is in the open position such as illustrated in Fig. 3, then steel wool pads 76 and 91 may be placed over the grooved surfaces of the blocks 35 and 45 respectively. While holding the abrasive materials against the blocks, the grills 60 and 80 are pivoted about rods 62 and 82 thereby compressing and forcing portions of the steel wool pads into the grooves 57 and 79.

When the grills have entered their respective groove patterns in the blocks 35 and 45, the latch bars 70 and 87 will be pivoted into slots 73 and 88 respectively. The wing nuts 75 and 90 are then tightened against the base 21 and the levers 89 respectively to draw and hold the grills 60 and 80 in the grooves 57 and 79 of the blocks 35 and 45. The steel wool pads 76 and 91 will thereby be securely held to the grooved surfaces of their respective blocks and the grills 60 and 80 will be below the plane of the cleaning surface of the steel wool pads.

The upper portion of the apparatus consisting essentially of grill 80, abrasive 91, block 45, frames 36, straps 89 and the connecting link 37 is pivoted in a counterclockwise direction (Figs. 3, 4 and 5) to move the steel wool pad 91 in contact with the upper surface of the strip 100. The latch bars 91 pivotally mounted on the frame 21 are then pivoted clockwise (Figs. 3, 4 and 6) into slots 93 (Fig. 1). The wing nuts 95 are tightened against the levers 36 to force the blocks 36 and 45 together and thereby force the two pads 76 and 91 against the lower and upper surface of the strip 100 to give frictional contact therewith to provide the cleaning action necessary.

When the pads 76 and 91 become worn or in need of replacement, the latch bars 91 are released and the upper block 45 pivoted clockwise (Figs. 3, 4 and 5) about pin 38 to separate the steel wool pads. With the blocks in the open position, the latches 70 and 87 are released from the frame 21 and the levers 89, and then the grills 60 and 80 are pivoted out of the grooves in the blocks (Fig. 3) to allow the steel wool pads 76 and 91 to be removed and replaced.

It is to be understood that the above-described ar-

rangements are simply illustrative of an application of the principles of this invention. Numerous other arrangements may be readily devised by those skilled in the art which will embody the principles of the invention and fall within the spirit and scope thereof.

What is claimed is:

1. An apparatus for cleaning surfaces of strip material which comprises a first block, a second block pivotally connected to the first block, said first and second blocks having a plurality of grooves therein on facing surfaces of the blocks, compressible abrasive material positioned on the grooved surfaces of the blocks, a separate grill pivotally mounted to each block over the abrasive material to enter the grooves to compress portions of the abrasive material within the groove, and latch means for holding the grills in the grooves so that the outer surfaces of the uncompressed abrasive materials extend beyond the outer surfaces of the grills.
2. An apparatus for cleaning surfaces of a moving strip material which comprises a stationary block, a frame pivotally mounted to said stationary block, a cover block resiliently mounted on the frame facing the stationary block, said blocks having grooves in the opposing surfaces thereof, a first grill pivotally mounted to the stationary block, a second grill pivotally mounted to the cover block, said grills having the elements thereof patterned to fit within the grooves, compressible abrasive materials positioned between the respective blocks and grills, latches mounted on each grill to force the grill against the abrasive and into the grooves, and latches mounted on the stationary block to hold the blocks together to force the compressible abrasive material against a moving strip material to be cleaned.
3. An apparatus for cleaning opposing surfaces of strip material which comprises a base, a first block rigidly mounted on said base, said block having surface grooves therein, a first grill pivotally mounted on said first block to enter the grooves formed therein, a compressible steel wool pad positioned between said first grill and first block, latch means mounted on said first grill for retaining the grill within the grooves, a frame pivotally mounted on said base to move toward the first block, latch means mounted on said frame for retaining the frame in position over the first block, a second block resiliently mounted on said frame facing the first block, said second block having surface grooves therein, a second grill pivotally mounted on said second block to enter into the grooves of the second block, a second compressible steel wool pad positioned between said second grill and second block, latch means mounted on said second grill to retain the grill within the grooves of the second block, and latch means for holding the blocks in spaced relationship.
